CLAIM

The ornamental design of a guitar strap, substantially as shown and described.

DESCRIPTION

FIG. 1 is a perspective view of the ornamental design of a guitar strap in accordance with this invention.

FIG. 2 is a rear perspective view of the FIG. 1 view of the ornamental design of a guitar strap in accordance with this invention.

FIG. 3 is a right perspective view of the FIG. 1 view of the ornamental design of a guitar strap in accordance with this invention.

FIG. 4 is a left perspective view of the FIG. 1 view of the ornamental design of a guitar strap in accordance with this invention.

FIG. 5 is a top perspective view of the FIG. 1 view of the ornamental design of a guitar strap in accordance with this invention; and,

FIG. 6 is a bottom perspective view of the FIG. 1 view of the ornamental design of a guitar strap in accordance with this invention.

The broken lines showing the guitar illustrates the environment of the claimed design and forms no part thereof.
